UNITED STATES PATENT OFFICE

159,811

REFRIGERATOR CONTAINER

Donald W. Hill, Decatur, Ill., assignor to Crown Cork Specialty Corporation, Decatur, Ill., a corporation of Illinois

Application December 20, 1948, Serial No. 150,273

Term of patent 14 years

(Cl. D44—1)

To all whom it may concern:

Be it known that I, Donald W. Hill, a citizen of the United States, residing at Decatur, county of Macon, State of Illinois, have invented a new, original, and ornamental Design for Refrigerator Container, of which the following is a specification, reference being had to the accompanying drawings, forming a part thereof.

Figure 1 is a top plan view of a refrigerator container, showing my new design.

Figure 2 is a side elevational view.

Figure 3 is a bottom plan view, and

Figure 4 is a vertical cross-sectional view with the closure removed.

I claim:

The ornamental design for a refrigerator container, substantially as shown.

DONALD W. HILL.
